UNITED STATES PATENT OFFICE.

MARTHA H. CONNOR, OF BALTIMORE, MARYLAND, ASSIGNOR TO THE TIN DECORATING COMPANY OF BALTIMORE, OF BALTIMORE, MARYLAND, A CORPORATION OF NEW JERSEY.

DESIGN FOR A BOX FRONT.

Application filed September 26, 1923. Serial No. 7,333. Term of patent 3½ years.

To all whom it may concern:

Be it known that I, MARTHA H. CONNOR, a citizen of the United States, residing in the city of Baltimore, State of Maryland, have invented a new, original, and ornamental Design for a Box Front, of which the following is a specification, reference being had to the accompanying drawing, forming a part thereof, wherein the figure is a perspective of my new design for a box front.

What I claim is:

The ornamental design for a box front, as shown.

MARTHA H. CONNOR.
